UNITED STATES PATENT OFFICE.

THOMAS BUTTERWORTH HARRISON, OF PHILADELPHIA, PENNSYLVANIA.

GAS-BURNER.

No. 884,819.

Specification of Letters Patent. Patented April 14, 1908.

Application filed September 20, 1907. Serial No. 393,844.

To all whom it may concern:

Be it known that I, THOMAS BUTTERWORTH HARRISON, a subject of the King of Great Britain, residing at Philadelphia, in the county of Philadelphia and State of Pennsylvania, have invented new and useful Improvements in Gas-Burners, of which the following is a specification.

This invention relates to gas burners and 10 one of the principal objects of the same is to provide means for automatically regulating the flow of gas through the burner.

Another object of the invention is to provide a sliding aluminium valve disk which is 15 adapted to be moved by the pressure of gas to regulate the flow of gas through the burner.

These and other objects may be attained by means of the construction illustrated in 20 the accompanying drawing, in which:—

Figure 1 is a central vertical section through a gas burner made in accordance with my invention. Fig. 2 is a plan view of the plug or fitting at the lower end of the 25 burner. Fig. 3 is a perspective view of a hollow tapering perforated valve seat. Fig. 4 is a perspective view of the sliding valve disk, looking at the under side.

Referring to the drawing for a more specific description of my invention, the numeral 1 designates the plug or fitting for the lower end of the burner, said fitting being 30 interiorly screw threaded as at 2 to fit an ordinary gas supply pipe, said fitting having an annular bead 3 and the upper end of said fitting being screw threaded as at 4 to fit the burner tube 5. The upper end of the fitting 1 is preferably concave and provided with a series of perforations 6. The threaded portion 40 4 fits the threaded portion 7 of the burner tube. A wire shaft or spindle 8 is fitted in the concaved top of the fitting 1 and extends upward into a hollow tapering thimble 9 having a perforated top 10, said thimble being secured in place in the burner tube 5.

An aluminium valve disk 11 having a downwardly projecting peripheral flange 12 is provided with a central aperture 13 said disk being mounted upon the spindle 8 to 50 slide freely thereon. An ordinary gas tip 14 is secured in the upper end of the burner tube 5.

The operation of my invention may be briefly described as follows:—When the gas 55 is turned on through the burner if the pressure is excessive, the aluminium disk will rise upon the spindle 8 to a position to regulate the flow of gas through the burner. Should the pressure be sufficient the valve disk 60 would rise to the position shown in dotted lines in Fig. 1, then the full pressure of gas passes through the perforations 6, but permits only a slight flow to pass through between the top part of the valve disk 11 and 65 the seat of said valve.

From the foregoing it will be obvious that a burner made in accordance with my invention automatically regulates the flow of gas, that the invention is simple in construction, 70 can be readily attached to any gas supply pipe and is very efficient for the purpose.

Having thus described the invention, what is claimed as new, is:—

A gas burner comprising a tube, a hollow 75 tapering thimble provided with a perforated top secured to said burner tube and provided with an open lower end, a fitting provided with a perforated top secured in the lower end of said burner tube, an upwardly projecting spindle secured to said perforated top and extending into the open lower end of said thimble, and an aluminium valve disk having a downturned peripheral edge mounted to slide upon said shaft or spindle. 85

In testimony whereof I affix my signature in presence of two witnesses.

THOMAS BUTTERWORTH HARRISON.
